(57) **CLAIM**

The ornamental design for a wall-mount spout, as shown.

DESCRIPTION

FIG. 1 is a perspective view of the wall-mount spout according to the invention; and

FIG. 2 is a top view of the spout;

FIG. 3 is a left-side elevational view, the right side being a mirror image thereof; and,

FIGS. 4, 5, and 6 are bottom, front, and rear elevational views, respectively.
